(57) **CLAIM**

The ornamental design for a fence line weed guard with anchor, as shown and described.

DESCRIPTION

FIG. 1 is an isometric view of a strip portion of indefinite length, a left hand member portion, and a right hand member portion of a fence line weed guard with anchor;

FIG. 2 is an isometric view of the strip portion of indefinite length of the fence line weed guard with anchor;

FIG. 3 is a front view of FIG. 2, wherein a rear view is a mirror image of the front view;

FIG. 4 is a left-hand side view of FIG. 2, wherein a right-hand side view is a mirror image of the left-hand side view;

FIG. 5 is a top view of FIG. 2;

FIG. 6 is a bottom view of FIG. 2;

FIG. 7 is an isometric view of the left hand member portion of the fence line weed guard with anchor;

FIG. 8 is a front view of FIG. 7, wherein a rear view is a mirror image of the front view;

FIG. 9 is a left-hand side view of FIG. 7;

FIG. 10 is a right-hand side view of FIG. 7;

FIG. 11 is a top view of FIG. 7;

FIG. 12 is a bottom view of FIG. 7;

FIG. 13 is an isometric view of the right hand member portion of the fence line weed guard with anchor;

FIG. 14 is a front view of FIG. 13, wherein a rear view is a mirror image of the front view;

FIG. 15 is a left-hand side view of FIG. 13;

FIG. 16 is a right-hand side view of FIG. 13;

FIG. 17 is a top view of FIG. 13; and,

FIG. 18 is a bottom view of FIG. 13.
